(57) **CLAIM**

The ornamental design for a surface configuration of a vehicle and toy, as shown and described.

DESCRIPTION

FIG. 1 is a perspective view of a first embodiment of a surface configuration of a vehicle and toy according to our novel design;

FIG. 2 is a front view of the first embodiment of the surface configuration of a vehicle and toy according to our novel design;

FIG. 3 is a left view of the first embodiment of the surface configuration of a vehicle and toy according to our novel design;

FIG. 4 is a right view of the first embodiment of the surface configuration of a vehicle and toy according to our novel design;

FIG. 5 is a rear view of the first embodiment of the surface configuration of a vehicle and toy according to our novel design;

FIG. 6 is a top view of the first embodiment of the surface configuration of a vehicle and toy according to our novel design; and,

FIG. 7 is a top view of a modified embodiment of the design shown in FIGS. 1-6.

The dash lines included depict environment and are not part of the claimed design.
